(57) **CLAIM**

The ornamental design for a writing instrument, as shown and described.

DESCRIPTION

FIG. 1 is a perspective view of a writing instrument in accordance with a first embodiment of my design;

FIG. 2 is a second perspective view thereof;

FIG. 3 is a right side elevational view with the side opposite being a mirror image thereof;

FIG. 4 is a top plan view thereof;

FIG. 5 is a bottom plan view thereof;

FIG. 6 is a front view thereof;

FIG. 7 is a rear view thereof;

FIG. 8 is a perspective view of a writing instrument in accordance with a second embodiment of my design;

FIG. 9 is a second perspective view thereof;

FIG. 10 is a right side elevational view with the side opposite being a mirror image thereof;

FIG. 11 is a top plan view thereof;

FIG. 12 is a bottom plan view thereof;

FIG. 13 is a front view thereof; and,

FIG. 14 is a rear view thereof.
